UNITED STATES PATENT OFFICE.

CHARLES H. GERSCH, OF CHICAGO, ILLINOIS.

FENCE-POST.

SPECIFICATION forming part of Letters Patent No. 450,385, dated April 14, 1891.

Application filed October 11, 1889. Serial No. 326,741. (No model.)

To all whom it may concern:

Be it known that I, CHARLES H. GERSCH, residing at Chicago, in the county of Cook and State of Illinois, and a citizen of the 5 United States, have invented a new and useful Improvement in Fence-Posts, of which the following is a specification, reference being had to the accompanying drawings, in which—

Figure 1 is an elevation showing a complete 10 fence. Fig. 2 is a central vertical section through a single post. Fig. 3 is a top view of the base, the post being in section. Fig. 4 is a side elevation of the base.

This invention relates to improvements in 15 fence-posts. Its object is to provide an improved terra-cotta base for supporting the post, which I accomplish as illustrated in the drawings and as hereinafter described. That which I claim as new will be pointed out in 20 the claim.

In the drawings, A represents a fence-post, which may be made in any suitable form and adapted to support any style of fence, such as the picket-fence shown, or a wire fence, or 25 other style of fence requiring a post.

B represents the base, which may be made of terra-cotta, pottery, or common earthenware, and is designed to be set in the ground to support the post in the desired position. 30 This base B has a central opening through its entire length, which diminishes in diameter toward its upper end.

The lower end of the post A is placed in the upper end of the base B, and the space 35 between the post A and the base B is filled with cement *b*, which firmly holds the post in the base B. As the interior opening of the base B is tapered upward, the post cannot be drawn out after the cement has set around 40 it by winds or accidents on account of the wedging action of the tapered opening.

D is an iron ring securely set with cement on the top of the base B, a suitable notch being formed in the terra-cotta base to receive it and make the surface even. This ring D 45 prevents the base from being cracked by frost or broken either by accident or by the wedging of the post A in the tapered opening.

a is a ring or flange, which may be secured to the post, or, if the post is made of cast 50 metal, may be cast thereon. This flange or ring rests upon the top of the base B, supporting a part of the weight of the post, and also serving to protect the top of the base B.

The base so made of terra-cotta furnishes 55 a firm support for the post and is not affected by rust, as metal posts, or by rot, as wooden posts are, which are placed directly in the ground.

I am aware that concrete bases for posts of 60 different constructions have been heretofore used, and I do not claim such broadly; but

What I do claim as new, and desire to secure by Letters Patent, is—

The combination, with a fence-post A of 65 substantially uniform size throughout its lower part, of a terra-cotta base B, having a central longitudinal tapered opening extending through its entire length to receive the post and having a notch around its upper 70 end, an iron ring set in cement around the top in said notch, cement for securing the post in the tapered opening, and a flange or ring *a* on the post A, which rests upon the base B, all constructed and combined substantially as and for the purposes specified. 75

CHARLES H. GERSCH.
